UNITED STATES PATENT OFFICE.

HERMANN LIECHTY, OF BERNE, AND JACOB WERZ, OF GENEVA, SWITZERLAND.

BOGIE FOR RAILWAY-VEHICLES.

1,391,742.

Specification of Letters Patent. Patented Sept. 27, 1921.

Application filed July 21, 1920. Serial No. 398,025.

To all whom it may concern:

Be it known that we, HERMANN LIECHTY and JACOB WERZ, both citizens of the Swiss Republic, the former residing in Berne, 5 Switzerland, the latter in Geneva, Switzerland, have invented new and useful Improvements in Bogies for Railway-Vehicles, of which the following is a full, clear, and exact specification.

10 The object of this invention is a driving mechanism on the driving axle frames of railway vehicles which, on the one hand, contains in its interior a driving shaft for one axle of the bogie coupled through a universal coupling, and, on the other hand, is connected with the main frame of the vehicle by means of a universal joint in such a manner that it can automatically move aside at curves of the track, and thereby the bogie 20 axle can adjust itself radially to the curve.

It is already known in driven bogies of railway vehicles to insert universal joints or the like between the motor and the bogie axle in order to allow rocking of the bogie 25 in traversing curves of the line. Moreover, it has already been proposed to arrange the driving motor on the bogie itself. From these known arrangements the present invention is distinguished by the fact that the 30 connection of the motor fixed on the main frame of the vehicle, with the bogie having a slide guiding on the main frame, is realized by means of a hollow drive and draw bracket or framework inclosing the 35 driving shaft, coupled rigidly with the bogie, but by articulation with the motor, and arranged to transmit the driving as well as the drawing strains of the mechanisms. The improved hollow bracket thus acts so as 40 to transmit the drawing force from the running wheel to the vehicle and through its interior drive to transfer the rotating force from the motor to the running wheel. This arrangement gives rise to a simple and compact 45 drive and draw device for the bogie with a fixed motor on the vehicle frame, which is quite different from the usual universal joint drive.

The accompanying drawing represents an 50 embodiment of the present invention:

Figure 1 shows an example of application of the same;

Fig. 2 is a horizontal longitudinal section through the driving and drawing bar.

The hollow body or bracket *a* of the new 55 driving and drawing bar is articulated by means of the two-part socket *b* and the head piece *c* of a spherical joint on the motor frame *d* fixed to the main frame of the vehicle. It contains within it a driving shaft *e* 60 supported therein, which on the one hand is connected by means of the conical gear *f* to the driven axle *g* of the bogie, while on the other hand it is positively connected by a Cardan joint *h* to the shaft *i* of the driving 65 motor. In this way, the drive is transmitted from the motor to the bogie axle *g*. In track curves, owing to the swiveling motion of the driving bar in the spherical joint *b*, *c*, the bogie is allowed to automatically displace 70 itself laterally without affecting the positive drive of its driven axle *g*, the driving shaft *e* being also allowed to suit to this lateral displacement by virtue of its connection in the Cardan joint *h*. Further, oscillations of the 75 driving bar upward or downward are allowed to take place by means of the said joints without hindering in any way the positive drive. Thus, a free mobility of the driving bar to all sides is obtained while 80 permanently maintaining the positive drive of the driven bogie axle *g*.

Instead of the spherical joint *b*, *c*, there may also be employed a Cardan joint; in analogous manner the inner Cardan joint 85 could be replaced by a spherical joint. By the term "universal joint" we understand these kinds of joints as well as any other articulation joint which allow of oscillatory movement to all sides. Obviously the 90 bogie, which according to Fig. 2 has one single axle, may also comprise two axles of which the one would serve as driving axle, while the other would be connected to the first one by means of crank gear, toothed 95 gear and the like.

What we claim is:

In a drive and draw device for bogies of railway vehicles, a driving axle on the bogie, a driving and drawing hollow bracket coupled to said axle, a rotary driving shaft within said bracket, a motor fixed on the main frame of the vehicle to actuate said driving shaft, a universal joint for connect-

ing the latter to said motor, power transmission means between said driving shaft and the driving axle of the bogie and a universal joint for connecting the hollow bracket to the main frame of the vehicle, substantially as and for the purpose described.

In witness whereof we have hereunto

signed our names this 6th day of July, 1920,
in the presence of two subscribing witnesses. 10

HERMANN LIECHTY.
JACOB WERZ.
